UNITED STATES PATENT OFFICE

JAMES C. OLSEN, JR., AND HARRY L. BOTTLE, OF ANDERSON, INDIANA, ASSIGNEES TO
ANDERSON STOVE COMPANY, OF ANDERSON, INDIANA, A CORPORATION OF INDIANA

STOVE

Application filed April 7, 1930. Serial No. 442,072.

Our invention relates particularly to cooking ranges, and our main object is to provide an organization in which the fuel supply manifold and the valves or switches for the heating elements in the cooking-top are arranged at one end of the range below its top-frame and with the valve controls extending through the top-frame and preferably flush with its surface. Other objects will be apparent from the disclosure in connection with the embodiment of our invention shown in the drawing.

Referring to the accompanying drawing which illustrates one form or exemplification of our invention, Fig. 1 is a top plan view of a range showing the location of the oven section, the cooking-top section, the gas-manifold and the control valves; Fig. 2 is a view in front elevation of the stove equipped with the parts as shown in Fig. 1; Fig. 3 is a detail view in cross-section on the line 3—3 in Fig. 1, omitting the lighter for convenience of illustration; Fig. 4 is a detail sectional view on the line 4—4 of Fig. 3, showing the supports for the drip-pan and drawer in the cooking-top section; Fig. 5 is a detail top-plan view of the end shelf of the cooking-top with wells for the handles of the valves or switches, and Fig. 6 is a detail view partly in elevation and partly in section on the line 6—6 in Fig. 1, showing the arrangement of the gas-manifold, end shelf and one of the burner-valves and its handle. In the form shown in the drawing the parts are arranged with the oven-section of the range at the left hand side of the cooking-top, and it is to be understood that this arrangement can be reversed to locate the oven-section at the right hand side of the cooking-top, as our invention is applicable to both of these organizations.

In the drawing the reference numeral 1 designates the frame of the stove; 2 the oven-section comprising the usual upper baking oven and lower broiling oven having a suitable center-heat gas burner 3, and 4 the burner-box of the cooking-top in which any suitable number of burners 5 are supported beneath the grid plates 6 of the top frame 7 of the cooking-top. The frame 7 may project laterally beyond the end of the burner-box

to form an end shelf 8, or the frame may terminate flush with the end of the range and the shelf 8 may be a separate part removably supported on the frame and flush therewith; in either case the frame and shelf have down-turned marginal flanges. The gas-manifold 9 is located at one end of the range below the shelf; when the shelf is unitary with the frame 7 the manifold is fastened to it with a suitable clamp, and when a removable shelf is employed the manifold is held in place by a bracket bolted to the range. The manifold is connected at its inner end with a suitable gas supply (not shown), and its valve-controlled nozzles or jets 10 are alined with the feed-tubes 11 of the burners 5, each tube having a suitable air-mixer 12. Each jet 10 is governed by a valve or cock 13, having a handle 14 projecting upwardly through an elongated opening 15 in the shelf 8, which is suitably marked with "On" and "Off" signs at the ends of the openings to indicate the corresponding positions of the valves, as shown for example in Fig. 5. In practice we form the shelf 8 with depressions or wells 16 above the valves or cocks into which their handles 14 project through the openings 15 in the floors of the wells in convenient position for easy manipulation, the arrangement preferably being such that the handles do not project above the plane of the shelf and are in alinement and move in the same transverse line or plane, and the "On" and "Off" markings are on the floor of the wells and respectively at their corresponding ends and in the direct line of vision of the person manipulating the handles, all as shown for example in Figs. 1, 5 and 6. In the form here shown each well 16 is formed to accommodate a pair of valve handles, but they may be made separately for the corresponding handles, or a single well for all the handles may be provided. The manifold is connected by a feed pipe 17 with a valve-controlled nozzle or jet 18 alined with the oven-burner feed-tube 19 having the usual air-mixer 20, and the jet 18 is governed by a valve or cock 21 having an operating rod 22 extending forwardly under the top-frame at the inner side of the burner-box toward the front of the range and ter-

minating below a well or depression 23 in the front portion of the frame similar to the wells 16 and into which its operating handle 24 extends, as shown for example in Figs. 1, 2 and 3. Thus the valves and controls for all the burners are under the cooking-top frame, the handles for all the burners extend through it and their ends are approximately flush with it, and they can be manipulated through the frame by the operator at the front of the range and without any exposure to back-firing of the burners. Also, by locating the valves and controls as described the drip-pan 25 can be provided with a vertical front piece 26 forming a closure for the open front of the burner-box and having a handle 27 so that the pan can be conveniently removed, and when it is in place and a utility drawer 28 is used the range has the appearance and effect of a two-drawer front. The cooking-top has suitable opposite guide support 29 for the pan and drawer.

A suitable lighter 30 connected by a feed-pipe 31 to the manifold may be employed for the burners 5, and its valve-control handle 32 projects upwardly into a suitable well 33 in the frame 7 adjacent to the line of the wells 16. Hooks 34 for hanging utensils may be provided on the burner-box and base band 30 of the stove.

While we have shown a range of the cabinet type it is obvious that the oven section and its associated burner and control elements may be omitted, and that the cooking-top section and its associated elements will provide a complete cooking-top unit. In either case the cooking-top may be open or closed, the burners may be of suitable type to utilize gas, gasoline, kerosene or crude oil, or the heating elements may be electrically operated. The manifold and its associated parts may be arranged below the shelf at either end of the range to provide a right-hand or left-hand range. Various changes in the form and arrangement of the parts may be made without departing from the scope of our invention.

We claim:

1. In a cooking range, a cooking-top frame 50 having a plurality of openings in one end, a fuel supply manifold, a plurality of heating elements in the cooking-top, fuel-feeding means between said elements and manifold, and valves beneath the frame controlling said 55 fuel-feeding means and having their handles extending through said openings in all positions of the handles, accessible for manipulation from above said frame.

2. In a gas range, a cooking-top frame having a shelf extending at one end beyond the body of the range and provided with a plurality of wells having openings in their floors, a gas manifold, a plurality of burners in the cooking-top, and valves below the shelf controlling the flow of gas from the manifold to

the burners and having their operating handles extending through the openings in the well-floors and flush with the top of said shelf.

3. In a gas range, a cooking-top section 70 having a top-frame and a plurality of burners, a gas-manifold beneath one end of said frame, an oven-section at the opposite end of said frame, a gas-burner in the oven-section, valves below said frame controlling the flow of gas from the manifold to the burners, and valve handles extending upwardly through the top-frame.

4. In a cooking range, a top-frame having a well provided with an elongated slot in its 80 floor, a burner, means to supply heat to the burner, a valve for said supply means, and a handle for the valve extending upwardly through said slot into said well.

5. A gas range having an oven-section provided with a burner, a cooking-top section 85 provided with a plurality of burners and a top-frame formed with marginal wells having openings in their floors, gas-supply devices including valves arranged below the top-frame, and valve handles in the wells extending through their floor openings.

6. A range having a burner-box provided with a plurality of heating elements, a top-frame projecting beyond one end of said box, control devices for said heating elements below the projecting end of said frame and having their handles extending through it, and a drip-pan in said burner-box having an upwardly extending front piece forming 100 a closure for the front of said box.

7. A range having a burner-box provided with a plurality of heating elements, a top-frame projecting beyond one end of said box, control devices for said heating elements below the projecting end of said frame and having their handles extending through it, a drip-pan in said burner-box having an upwardly extending front piece forming a 105 closure for the front of said box, and a drawer 110 in the range below said drip-pan.

8. A range comprising an oven-section at one end provided with a burner, a burner-box at its other end provided with a plurality 115 of burners, a top-frame extending beyond the free-end of the burner-box, a gas manifold below the top-frame extension, fuel-feeding means between the manifold and burners including valves having upwardly projecting handles, the valves for the burner-box burners being located below the extension of the top-frame and the valve for the oven-burner being located below the inner end of the top-frame, and the top-frame having openings 120 in line with the valve-handles and through which said handles extend.

9. A range comprising an oven-section at one end provided with a burner, a burner-box 125 at its other end provided with a plurality of 130

burners, a top-frame having a shelf extending beyond the free end of the burner-box, a gas-manifold below said shelf, fuel-feeding means between the manifold and burners 5 including valves having upwardly projecting handles, the valves for the burner-box burners being located below said shelf and the valve for the oven-burner being located below the inner end of the top-frame, and wells 10 in the top-frame in line with the valve handles and having slots in their floors through which said handles extend.

In testimony whereof we affix our signatures.

15 JAMES C. OLSEN, JR.
HARRY L. BOTTLE.
